UNITED STATES PATENT OFFICE

FRANKLIN P. NICKERSON, OF CLEVELAND, OHIO, ASSIGNOR TO THE W. S. TYLER COMPANY, OF CLEVELAND, OHIO, A CORPORATION OF OHIO

SCREENING APPARATUS

Application filed February 9, 1928. Serial No. 253,050.

The present invention relates, as indicated, to a screening apparatus, and more particularly to improved means for applying material to be screened to a screening machine. 5 The primary object of the invention is to provide a chute for sand or like flowable solid material which will deliver a substantially uniform layer of such material over a relatively wide area. To the accomplishment of 10 the foregoing and related ends, said invention, then, consists of the means hereinafter fully described and particularly pointed out in the claim.

The annexed drawing and the following 15 description set forth in detail certain mechanism embodying the invention, such disclosed means constituting, however, but one of various mechanical forms in which the principle of the invention may be used.

20 In said annexed drawing:

Fig. 1 is a side elevation of a chute of the type contemplated by the present invention in assembled relation with a screening machine; Fig. 2 is a broken front elevation of 25 the same; Fig. 3 is a plan view of the distributor plate; Fig. 4 is a longitudinal section therethrough; and Fig. 5 is an end view thereof.

Referring more particularly to the drawings, the reference numeral 1 indicates a screening machine resting upon a base 2 and provided with an intake hopper 3 in which there is mounted an inclined plate 4 for directing material discharged into said hopper 30 on to a screen 5 mounted within the machine. Mounted above said hopper is a diffuser comprising a casing 6 having an inlet opening 7 at its top and a discharge opening 8 at its bottom, said discharge end entering the hopper 3. The casing 6 is flared outwardly from 35 its top to its bottom as is clearly shown in Fig. 2. Thus the inlet end 7 of the casing is of substantially the width of the discharge mouth of the usual storage hopper (not 40 shown), while the discharge end 8 of the casing has a width substantially equal to the width of the screen 5.

An inclined plate 9 mounted in the intake 45 end 7 of the casing 6, directs material discharged into said intake end 7 toward the

upper end 10 of a diffuser plate 11 which rests upon the inclined floor of the casing 6. The casing 6 is provided adjacent its upper end and in its front wall with a door 12 hinged to the casing as at 13 and provided with a handle 14 to facilitate manipulation 55 thereof.

The plate 11 is formed as a trapezoidal pyramid, its base being formed with a short side 15 and a much longer side 16 parallel therewith, an angular sides 17 and 18 joining the ends of said sides 15 and 16. The triangular faces 19 and 20 are formed on the sides 15 and 16 respectively as bases, and the faces 21 and 22 are similarly formed on the 60 sides 17 and 18 as bases, all four of said faces meeting in a common apex 23. The plate is 65 suitably braced by ribs or legs 24 and 25, as indicated in Fig. 4.

It will be readily seen that, through the 70 use of the above described device, material may be discharged from the usual cylindrical pipe of relatively small diameter, and will be fed by said chute on to the screen as a broad sheet of substantially uniform thickness. The cylindrical stream of material will strike the plate 9 and be deflected against the upper edge 15 of the plate 11. Obviously 75 the material will tend, because of the cylindrical shape of the stream to pile up adjacent the center point of said edge 15, and the angles of the pyramid joining the face 19 with the faces 21 and 22 are such as to compensate for this piling tendency, and to cause a substantially uniformly thick sheet of 80 flowable material to slide down toward the base of the plate. The inclination of the faces 21 and 22 tends to spread the stream fanwise, but a certain portion of the material will overflow the corners joining the 85 face 20 with the faces 21 and 22 to prevent an actual partition of the stream. Thus the cylindrical stream of material is spread out into a relatively thin sheet of substantially uniform thickness and of a width corresponding to the width of the screen 5 before its discharge on to said screen. 90

Other modes of applying the principle of my invention may be employed instead of the one explained, change being made as re- 95 100

gards the mechanism herein disclosed, provided the means stated by the following claim or the equivalent of such stated means be employed.

5 I therefore particularly point out and distinctly claim as my invention:

For use with a machine having a wide intake hopper and a feed bin having a relatively small discharge mouth, means for 10 causing the narrow stream of flowable material discharged from said mouth to be fanned out to a width substantially equal to the width of said intake hopper, and for depositing substantially uniform amounts of 15 such material across the entire width of the machine, said means comprising a hollow casing adapted to receive such material from said discharge mouth and to discharge the same into said intake hopper, said casing having an inclined portion, the floor of said portion being flared outwardly from its top to its bottom, and a plate formed as a trapezoidal pyramid and having its apex directed upwardly from said floor, said plate resting 20 on said floor with the shortest side of its base adjacent the top of said casing.

Signed by me this 6th day of February, 1928.

FRANKLIN P. NICKERSON.
